UNITED STATES PATENT OFFICE.

ARCHIE LEE KITCHENS, OF BAGWELL, TEXAS, ASSIGNOR OF ONE-THIRD TO W. M. MOONEY, OF CLARKSVILLE, TEXAS.

ELECTRIC SWITCH.

Application filed February 28, 1922. Serial No. 540,032.

To all whom it may concern:

Be it known that ARCHIE LEE KITCHENS, a citizen of the United States of America, residing at Bagwell, in the county of Red River and State of Texas, has invented new and useful Improvements in Electric Switches, of which the following is a specification.

The object of the invention is to provide 10 a simple, inexpensive and efficient switch designed particularly for use in connection with incandescent electric lights, wherein the light may be dimmed or varied in intensity to suit the requirements of the operator as 15 for example in using the same as a night or sick room lamp or where a light which is of an intensity less than that which is afforded by the complete strength of the current is not required; and with this object 20 in view the invention consists in a construction and combination of parts of which a preferred embodiment is shown in the accompanying drawings, wherein:—

Figure 1 is a view of the switch in its 25 opened position.

Figure 2 is a similar view with the switch in its closed position.

The device consists of a base 10 carrying terminals 11 and 12 provided with binding 30 posts 13 and 14 for the attachment of the conductor wires 15 and 16 extending from any suitable source of energy. The terminal 11 is of spring or yielding construction and 35 consists of a tongue arranged in the path of a cam 17 carried by an operating lever 18 which is fulcrumed as indicated at 19 upon a suitable supporting bracket 20.

Mounted upon the terminal 12 for adjustment longitudinally thereof and of the base 40 is a contact 21 consisting of a pin or its equivalent, and in connection therewith is arranged a set-screw 22 for engagement with the terminal to secure the contact element in its adjusted positions, while yieldingly supported in the path of movement of the yielding terminal 11 and adapted for engagement 45 with the contact 21 is a resistance contact 23 consisting of a bar having a relatively low co-efficient of conductivity and which is 50 arranged for actuation by the terminal with which it contacts at its free end, to permit of bringing the resistance contact element into engagement with the first-named contact element at a point in the length of the former

which is determined by the adjustment of 55 the latter.

In operation the current of electricity in passing for example from the terminal 12 to the terminal 11 must pass through the contact element 21 and through that portion of the resistance contact element which is between the point of contact of the terminal 21 with the contact element 23 and the extremity of the contact element 23 which is in engagement with the terminal 11, and obviously by varying the adjustment of the contact element 21 with relation to the length of the contact element 23, a greater or less length of the contact element 23 may be induced into the circuit to correspondingly 70 vary the resistance and therefore the intensity of a light produced by a lamp included in the circuit.

In order that the resistance contact element may be movable out of and into contact with the relatively stationary but adjustable contact element 21 without bending or flexing the former, as in the event that the material of which the resistance contact element is made or provided will not permit of bending or flexing, the said resistance element may be supported by a spring similar to the terminal 11 which in practice may be of brass, copper or any equivalent thereof and is preferably of such dimensions as to 85 permit of the bending or flexing thereof under the operation of the actuating cam.

Having described the invention, what is claimed as new and useful is:—

1. A switch for the purpose indicated having terminals of which one is movable to close and open the circuit, and contact elements for engagement to complete the circuit, one of which is of resistance offering material and is arranged in the path of and in contact with the movable terminal for movement thereby into engagement with the other contact element.

2. A switch for the purpose indicated having terminals of which one is movable to close and open the circuit, and contact elements for engagement to complete the circuit, one of which is of resistance offering material and is arranged in the path of and in contact with the movable terminal for movement thereby into engagement with the other contact element, one of said contact elements being adjustable to vary the

length of that portion of the first-named contact element which is between the point of engagement of the contact elements and the point of contact of the first-named element with the movable terminal.

3. A switch for the purpose indicated having terminals of which one is movable to close and open the circuit, and contact elements for engagement to complete the circuit, one of which is of resistance offering material and is arranged in the path of and in contact with the movable terminal for

movement thereby into engagement with the other contact element, the second-named contact element being movable in a path parallel with the length of the first-named contact element to vary the point of contact of said elements toward and from the point of contact of the first-named element with the movable terminal. 15

20 In testimony whereof he affixes his signature.

ARCHIE LEE KITCHENS.
